UNITED STATES PATENT OFFICE.

NELSON S. WELK, OF ATHENS, OHIO, ASSIGNOR TO THE MCBEE BINDER CO., OF ATHENS, OHIO, A CORPORATION OF OHIO.

FILING TRAY.

Application filed May 8, 1926. Serial No. 107,574.

My invention relates to the stationery art, and particularly to that class thereof, pertaining to trays for receiving cards, and the like, for filing.

5 The object of my invention is to provide a filing tray equipped with a longitudinal side adapted to drop, so as to make the cards more easily accessible, and further, to cause said side when so dropped, to assume a position 10 for functioning as an auxiliary base to receive the cards desired to be pushed, or placed, out of alignment with the other filed cards.

A further object is to provide a stop against 15 which the cards so displaced will abut, so as to cause all the displaced cards to be in orderly and neat arrangement for quick reference.

I accomplish the above objects by a construction, wherein the mechanical means hinging the side and controlling its swing also 20 functions as the stop or abutment, as will be apparent from the following specification, reference being had to the accompanying drawings, in which

Fig. 1 shows a perspective view of my filing 25 tray, the side being dropped to form the auxiliary base;

Fig. 2 shows a plan view of the same, and

Fig. 3 shows a sectional view taken on the line 3—3 of Fig. 1.

30 Referring to the accompanying drawing, the reference numeral 10 is used to indicate the base of my tray. Numerals 11 and 12 indicate the front and rear sides thereof, respectively, and numeral 13, one longitudinal side 35 thereof.

My invention resides in the construction which forms the other longitudinal side of my tray, and its manner of operation and its functioning. This side is represented by the 40 numeral 14 and is hinged at its base to the base 10, of the tray, as shown at 15. It is provided on its inner surface with two, or more, triangular shaped brackets 16, each of which is provided with an elongated slot 17. 45 Mounted within these slots is a rod 18, provided with arms 19 and 20, the ends of the rod being pivotally mounted to the body of the tray, as shown at 21 and 22.

The construction of the parts is such that as 50 the side 14 swings, it carries with it the rod 18, which travels in the slots in the brackets, as the side swings either upwardly or downwardly. These slots are arranged in their brackets, so that when the swinging side has 55 reached a position on a plane with the base

of the tray, the rod abuts against the end of the slots in the brackets, and thus limits the movement of the swinging side and positions it in proper alignment with the base of the tray. In addition to this, the ends of the slots 60 against which the rod abuts, are elevated from the swinging side, so that when the rod positions the swinging side, it also positions itself above the plane of the side and parallel therewith.

I have provided means for locking the swinging side in position, the locking means consisting of the projecting recessed lugs 23, one on either side of the tray, which receives the recessed ends of the metal strap 24, the 70 lugs and strap being so formed and arranged that when the strap drops into the recesses in the lugs and locks the side, the said side will be in proper position to form the longitudinal side for the tray.

In order to provide for a slight upward and downward movement of the swinging side when it is at its upper limit of movement so as to permit the metal strap to be elevated somewhat so that it may drop into the recesses in the lugs, to lock the side, I have provided hinging means for the side 14, with a slight play which is brought about by providing elongated slots in each end of the tray into which the male members of the hinging 85 means extend. It is obvious, this will permit a slight upward and downward movement of the male member of the hinge, within the female member.

In practical operation, the cards being filed 90 in the tray, if it is desired by the operator to displace some of the said cards for reference, the swinging side is dropped to its downward position. The rod 18 positioned above the lowered side and parallel with the said side 95 and also the other longitudinal side of the tray, forms a stop or an abutment against which the displaced cards abut and are thereby positioned. When the cards have either been placed back in the file or removed, the 100 swinging side is elevated and locked in its normal position, thereby forming one of the longitudinal sides of the tray.

I am aware that there are several filing 105 trays on the market provided with dropping sides, and also with abutment means for displaced cards. However, I am not aware that such a structure as I have invented and herein disclosed, comprising means for dropping a side, combined with means for forming an 110

abutment for displaced cards, has heretofore been used or disclosed.

Having thus described my invention, what I claim and desire to secure by Letters Patent of the United States is:

1. A filing tray provided with a base and sides, one longitudinal side being hinged to the base; means to position the swinging side in a substantially horizontal plane when open, said means also comprising an abutment stop for displaced cards; and means to lock the swinging side in closed position to the tray.

2. A filing tray comprising a base and sides,

one longitudinal side being hinged to the base to provide for a swinging movement outwardly; a rod pivoted to the tray and secured, for slidable movement therein, to brackets attached to the hinged side to provide means for positioning the swinging side in a substantially horizontal plane when open, said rod also comprising an abutment stop for displaced cards, and means to lock the swinging side in closed position forming a side of the tray, substantially as shown and described.

NELSON S. WELK.
